UNITED STATES PATENT OFFICE.

FREDERICK SEABERG, OF CHICAGO, ILLINOIS, ASSIGNOR TO NATIONAL DUMP CAR COMPANY, OF CHICAGO, ILLINOIS, A CORPORATION OF MAINE.

DUMP-CAR.

1,011,254.

Specification of Letters Patent. Patented Dec. 12, 1911.

Application filed September 21, 1909. Serial No. 518,854.

To all whom it may concern:

Be it known that I, FREDERICK SEABERG, a citizen of the United States, residing at Chicago, in the county of Cook and State 5 of Illinois, have invented certain new and useful Improvements in Dump-Cars, of which the following is a specification.

The object of my invention is to provide improved operating mechanism for the 10 doors of dump cars.

I have illustrated the invention as applied to an ore car having sloping ends and a central hopper bottom toward which the lower side inclosing walls also slope. 15 While the invention is particularly adapted to this type of car, it will be obvious that its utility is not restricted thereto, and that the principle of my invention, as hereinafter described and claimed, may be applied to cars of other types.

In the drawings—Figure 1 is a cross sectional view taken at about the center of the car and showing the operating mechanism. Fig. 2 is a view similar to Fig. 1, 25 showing the doors in open position. Fig. 3 is a view similar to the preceding views, but for the sake of clearness showing only part of the operating chains. Fig. 4 is a view similar to Fig. 3, but showing the 30 operating chains omitted from that view. Fig. 5 is a plan view of the car. Fig. 6 is a fragmentary side elevation.

The body of the car to which I have shown my invention applied comprises vertical side walls 1 and sloping ends 2.

Plates 3 secured to the lower parts of the side walls also slope inwardly toward the central hopper opening, the inner parts of the sloping sections 3 being bent vertically 40 downward, as indicated at 4. The parts 3 and 4 may be constructed individually or of separate plates, as illustrated. The dump doors 5 in their closed position are horizontal and have upwardly projecting outer edges, which at their upper extremities 6 are hinged to a fixed part of the car. It will be noted that the inward sloping side sections 3 in connection with the lower part of the vertical sides 1, together with 45 the horizontal members 7, form box girders extending along each side of the car, the vertical parts of the doors extending upwardly into these box girders and being there hinged. By hinging the doors above 50 the plane of the door opening in this manner, a full opening of the doors may be se-

cured without lowering their inner edges as far as would be the case if the doors were hinged in the plane of the door opening.

The doors are operated by means of reciprocal shafts 8 which rest upon tracks 9 extending transversely of the car, the tracks 9 being suspended by upward extensions 10 from a fixed part of the car body. The tracks 9 incline downwardly 65 toward the car sides and at their upper extremities are provided with a horizontal section 11. It will be apparent that as the shafts 8 move downwardly along the tracks 9, the doors will be permitted to 70 move to the open position illustrated in Fig. 2, and that as the shafts are moved upwardly toward the center of the car, the doors will be raised to closed position, as illustrated in Figs. 1, 3 and 4. 75

In order to impart the requisite movement to the operating shafts 8, I provide a power shaft 12. A housing 14—15—16, extends transversely of the car from the lower extremity of the hopper bottom to 80 a point above the shaft 12, as clearly shown in Fig. 6. This housing may consist of vertical plates 14 and 15 connected by an inclined section 16 which may be formed integrally with the plate 15. The shaft 12 85 is journaled in brackets 17 secured to the plate 14, and the ends of the shaft 12 may project slightly beyond the car sides, where they may be rotated by means of a wrench, or otherwise, having a squared end for this 90 purpose.

Beneath the shaft 12 and in substantially the same plane therewith are sheaves 18 journaled upon trunnions 19 supported by the plates 14—15. The sheaves 18 are provided with parallel chain grooves. The shaft 12 is preferably continuous across the car, thus operating both doors simultaneously, but if desired it is apparent that it could be made in two parts meeting at the 100 center of the car, thus providing for operating the doors separately. One of the grooves in each of the sheaves 18 is engaged by a cable or chain 20 secured at its ends, as indicated at 21 and 22, to the shaft 105 12 and intermediate its ends, as indicated at 23, to the sheave 18. Preferably, the shaft 12 is provided with a spiral groove 24 to guide the chain in its winding thereon. The opposite ends of the chain 20 110 winds upon opposite sides of the shaft 12 from which it will be apparent that as the

shaft is turned in one direction the sheave 18 will be rotated and when the shaft is rotated in the opposite direction the sheave also will be rotated in the opposite direction.

As clearly shown in Fig. 4, the second groove in each of the sheaves 18 is occupied by a chain or cable 25 secured to the sheave at 26. The opposite end of the chain 25 is secured to the operating shaft 8. As clearly shown in Figs. 3 and 4, each of the sheaves 18 is provided with several spur teeth 27 adapted to engage a spur wheel 28 fixed to the shaft 8 when the latter rests upon the upper horizontal part 11 of the track 9. The track 9-11 is provided with projecting pins or teeth 28 which coact with the spur gear 28 upon the shaft 8.

Upon reference to Figs. 3 and 4, it will be apparent that when the shaft 12 is rotated in a direction to impart rotation to the sheaves 18 in the direction indicated by the arrows, the spur teeth 27 acting upon the spur gears 28 will cause the shaft 8 to roll downwardly upon the track 9. As soon as the shaft 8 reaches the inclined part 9 of the track the weight of the door and superimposed load will carry the shaft 8 to the bottom of the incline as illustrated in Fig. 2. During the movement of the shaft 8 downward along the track 9, the engagement of the spur gear 28 with the teeth 28' will cause said shaft to rotate, thereby winding up the chain 25 upon the shaft 8 and unwinding the chain 20 from the central part of the shaft 12 and winding the same about the outer part thereof. The positions occupied by the different elements when the doors are in open position are illustrated in Fig. 2. Referring to Fig. 2, it will be apparent that when the shaft 12 is rotated in such direction as to cause the sheave 18 to turn in the direction indicated by the arrow, chain 25 will be wound up on said sheave and unwound from the shaft 8. The turning of the shaft 8 caused by the unwinding of the chain 25 therefrom imparts rotation to said shaft, whereupon the engagement of the spur gear 28 with the teeth 28' causes the shaft 8 to travel upward along the track 9, raising the door 5 to closed position. In the closed position of the doors, the shafts 8 rest upon the horizontal part 11 of the track, in which position the weight of and upon the doors has no tendency to move the shafts 8.

It will be noted that the chain 25 winds upon the shaft 8 in line with the pitch circle of the gear 28. Otherwise stated, the winding drum 35 upon the shaft 8 is of the same diameter as the pitch circle of the gear 28, by reason of this relation the spur teeth 27 acting upon the spur gear 28 at the beginning of the door opening movement, as

shown in Fig. 4, in such manner that the chain 25 winds upon the shaft 8 without slack or strain at the time the shaft 8 is being forced from the level track section 11 by the spur teeth 27.

While the foregoing description and the drawings are confined to one specific embodiment of my invention, it will be apparent that the principle thereof may be applied in mechanisms of different specific forms.

I claim:

1. In a car of the class described, a power shaft, a sheave, gearing between said power shaft and sheave, a reciprocable door operating shaft, and a winding cable connection between said sheave and reciprocable shaft. 80

2. In a car of the class described, a power shaft, a counter shaft, a door operating shaft, and winding cable connections between said shafts. 85

3. In a car of the class described, a power shaft, a counter shaft, a door operating shaft, winding cable connections between said shafts, and means to cause said operating shaft to rotate when reciprocated and to reciprocate when rotated. 90

4. In a car of the class described, a rotatable power shaft, a rotatable and reciprocable door operating shaft, a counter shaft, 95 winding cables connecting said power shaft and counter shaft and connecting said counter shaft and operating shaft, and means to cause said operating shaft to reciprocate when rotated and to rotate when reciprocated. 100

5. In a car of the class described, a rotatable power shaft, a rotatable and reciprocable door operating shaft, a counter shaft, winding cables connecting said power shaft and counter shaft and connecting said counter shaft and operating shaft, a spur gear upon said operating shaft, coacting teeth upon a fixed part of the car, and means to cause said operating shaft to reciprocate 110 when rotated and to rotate when reciprocated. 105

6. In a car of the class described, a power shaft, a sheave in substantially the same plane with said power shaft, a reciprocable door operating shaft extending at substantially a right angle to said power shaft, gearing between said power shaft and sheave and a winding chain connection between said sheave and reciprocable shaft. 115

7. In a car of the class described, a power shaft, a sheave in substantially the same plane with said power shaft, a reciprocable door operating shaft extending at substantially a right angle to said power shaft, 125 gearing between said power shaft and sheave, a winding chain connection between said sheave and reciprocable shaft, a support for said reciprocable operating shaft, means to cause said operating shaft to rotate when 130

- reciprocated and to reciprocate when rotated, and a door resting on said operating shaft.
8. In a car of the class described, a hinged door, a power shaft extending transversely of the hinge axis of said door, a sheave in substantially the same plane with said shaft, a winding cable secured at its ends to said shaft and at an intermediate point to the circumference of said sheave, a reciprocable operating shaft parallel to the hinge axis of said door, and a winding cable secured to said operating shaft and to said sheave.
9. In a car of the class described, a hinged door, a power shaft extending transversely of the hinge axis of said door, a sheave in substantially the same plane with said shaft, a winding cable secured at its ends to said shaft and at an intermediate point to the circumference of said sheave, a reciprocable operating shaft parallel to the hinge axis of said door, a winding cable secured to said operating shaft and to said sheave, a support for said operating shaft, a spur gear secured to said operating shaft, and coacting teeth upon said support.
10. In a car of the class described, doors hinged adjacent the sides thereof, a power shaft extending transversely of the car above said doors, sheaves below and substantially in the vertical plane of said power shaft, a housing around said power shaft and sheaves and extending between the car sides, supports inclining downwardly toward the sides of the car, reciprocable operating shafts between said doors and supports, gearing between said power shaft and sheaves, winding cables secured to said sheaves and operating shafts, spur gears on said operating shafts, and coacting teeth on said supports.
11. In a car of the class described, doors hinged adjacent the sides thereof, a power shaft extending transversely of the car above said doors, sheaves below and substantially in the vertical plane of said power shaft, a housing around said power shaft and sheaves and extending between the car sides, supports inclining downwardly toward the sides of the car and having horizontal sections adjacent the center of the car, reciprocable operating shafts between said doors and supports, gearing between said power shaft and sheaves, winding cables secured to said sheaves and operating shafts, spur gears on said operating shafts, coacting teeth on said supports, and teeth fixed to said sheaves and adapted to mesh with said spur gears when said operating shafts are raised to said horizontal sections of said supports.
12. A car of the class described, comprising a horizontal bottom section, said horizontal bottom section comprising a hinged drop door, a shaft carried by the underframe of the car and serving to support the free edge of the door when in closed position, power mechanism comprising a flexible connection with said shaft, and means for displacing the shaft from its door supporting position to permit the shaft to drop.
13. A car of the class described comprising a horizontal bottom section, said horizontal bottom section comprising a hinged drop door, an operating shaft carried by the underframe of the car and serving to support the free edge of the door when in closed position, a power shaft, a flexible connection between said power shaft and operating shaft, and means for displacing the operating shaft from its door supporting position to permit the shaft to drop.
14. A car of the class described having a horizontal bottom section comprising a hinged drop door, a shaft carried by the underframe of the car and serving to take the direct vertical thrust of the load on the door when the door is closed and to transmit the load to the load carrying members of the car, an actuating device for said shaft, the actuating device including a flexible shaft raising element, and a gear mechanism to displace the shaft from its door supporting position.
15. A car of the class described having sloping ends and a central horizontal floor section, a hinged dump door in said central section, a shaft beneath said door and serving to transmit the load on the door when closed vertically to the load carrying members of the car, a power shaft extending transversely of the car above said first-named shaft, and a winding cable power transmitting connection between said shafts.
16. A car of the class described having a central unobstructed discharge opening, doors hinged at opposite sides of said opening at points above the body of said doors, inclined tracks sloping downward from the central part of said opening, a bodily movable supporting shaft beneath each door and supported on said tracks, means for moving said shafts upwardly on said tracks to close said doors, and means for imparting movement to said shafts in the opposite direction to release said doors.

In testimony whereof, I have subscribed my name.

FREDERICK SEABERG.
